CLAIM

The ornamental design for a decorative pattern for a child's shoe, as shown and described.

DESCRIPTION

FIG. 1 is a front perspective view of a decorative pattern for a child's shoe showing my new design;

FIG. 2 is a top plan view thereof;

FIG. 3 is a left side elevational view thereof;

FIG. 4 is a right side elevational view thereof; and,

FIG. 5 is a front elevational view thereof.

The broken line showing of a child's shoe is environmental only and forms no part of the claimed design.
